BANDLESS JORDAN PLUG

Alfred Dorman, Pittsfield, Mass., assignor to E. D. Jones & Sons Company, Pittsfield, Mass., a corporation of Massachusetts

Application December 5, 1934, Serial No. 756,025

5 Claims. (Cl. 92—27)

This invention relates to certain improvements in washing, beating or refining engines and similar machines used in the treatment of paper stock, and more particularly to improvements in the construction of tapered grinding elements of the type used in Jordan engines, and which are commonly known as "bandless" for the reason that the grinding bars or knives are attached without the use of encircling bands.

5 The particular embodiment illustrated is a Jordan roll or plug comprising a tapered plug which is rotatable within a casing and bears grinding bars which cooperate with the interior of the casing to refine the stock, which passes through the machine in an axial direction from the smaller to the larger end of the plug. Filler blocks, generally made of wood, are inserted between the grinding bars to give the proper operative depth to the bars. Grinding bars have heretofore been attached to the plug by means of longitudinal slots in which the bars are seated and locking arrangements in the form of bayonet joints or pin-and-shoulder engagements placed along the slots and which hold the bars securely to the plug against radial displacement. Such a construction is shown in my previous Patent No. 1,362,606. As the taper of the plug results in a wider spacing between grinding bars as they approach the large or discharge end of the plug, 15 it is often found necessary to employ one or more sets of shorter grinding bars, which are inserted between the longer bars at the discharge end of the plug. In consequence, it has been possible to employ solid filler blocks only by inserting them between the longer bars in a radial direction, which prevents the use of a positive or mortise engagement between the filler blocks and bars, the blocks being merely wedged between bars and frictionally held.

20 It is an object of this invention to provide a construction in which all parts, including the woods or filler blocks, are positively locked together by pin-and-shoulder, mortise or like engagements, while still rapidly and easily assembled, and in which individual bars may be removed with ease and without requiring that the whole device be taken down.

25 It is also an object of this invention to achieve the desired security and simplicity of assembly without undue multiplication of parts, and to this end, wherever possible, I have modified essential parts of the machine to perform additional functions.

30 The invention consists in certain novel parts and features of construction which will now be

fully described in connection with the accompanying drawing, in which:

Fig. 1 is a side view, partly in section, showing the invention as applied to the roll or plug of a Jordan engine;

5

Fig. 2 is a side view, partly broken away, of one of the grinding bars;

Fig. 3 is a longitudinal section along the line 3—3 of Fig. 4, partly broken away, showing the manner of affixing the grinding bars to the plug, 10 and

Fig. 4 is a cross section along the line 4—4 of Fig. 1, partly broken away, showing the form and manner of attachment of the various parts.

Referring to the general view of Fig. 1, the 15 plug body 1 is of the usual conically tapered form, has the usual axle 2, and bears grinding bars 3 and 4, the spaces between which are filled by wooden blocks 5 and 6. At its forward end is a cover plate 7 which is fastened to the plug 20 body by means of the screws 8 and at its rearward or discharge end another cover plate 9 similarly attached by screws 10. The particular embodiment shown has two sets of grinding bars. It is sometimes desirable to use more than two 25 such sets of bars of different lengths, and this can be done by merely reduplicating the arrangements of the invention about to be described.

The hollow plug 1 is formed with longitudinal 30 supporting slots 11 and 12 substantially co-planar with the plug axis and encircling slots 13 at right angles to them, forming raised oblong ridges 14. The longitudinal slots are designed to seat the grinding bars and the encircling slots are provided to permit insertion of locking projections 35 on the bars, their forward walls being undercut so as to form shoulders 15 under which the bar projections may be slid.

The grinding bars 3 and 4 differ in length but are similarly constructed, having, as shown in 40 Fig. 2, locking studs 16 and longitudinal ribs 17. The manner of attaching the grinding bars to the plug body is shown in Fig. 3, the bars being inserted radially in the slots 11 and 12 (as shown by the broken lines and accompanying arrow) 45 and then slid forward (as shown by the full lines and arrow) until the studs 16 come under the shoulders 15. Wood filler blocks 5 and 6 are employed, being so shaped as to fill the space between bars in the manner shown in Fig. 4 and 50 so grooved as to engage the ribs 17, providing a positive mortise or tongue-and-groove engagement with the bars. These fillers are accurately cut to length so as to permit assembly as indicated in Fig. 1.

55

In assembling the plug of the invention the longer grinding bars 3 are first inserted in the slots 11 and are slid forward until their studs 16 engage under the shoulders 15 and their ends 5 rest against the forward cover plate 7. The filler blocks 5 are now slid forwardly into the spaces between the bars and until their ends also rest against the plate. The rearward grinding bars 4 are placed in the slots 12 and the rearward fillers 6 slid into the open spaces between bars 3 and 4 in the same manner, except that these rearward blocks and bars rest against the ends of the forward filler blocks 5 instead of against a cover plate. The final step in assembly is to 10 attach the rear cover plate 9 and fasten it by means of the screws 10. When it is desired to remove any of the grinding bars, the cover plate 9 is taken off and the desired parts slid out rearwardly without interfering with adjacent members. 15

It will be observed that the various parts are held on the plug against longitudinal displacement by merely extending the cover plates radially to act as stops, a very desirable feature, 20 since the cover plates must be provided in any event to seal the plug interior against the stock, and utilizing them as stops avoids the complication of extra parts. 25

What is claimed is:

30 1. In a machine of the class described, and in combination, a forwardly tapered frusto-conical plug having full-length peripherally spaced supporting slots and part-length rearward supporting slots between said full-length slots, en- 35 circling grooves at right angles to the supporting slots, and undercut shoulders extending rearwardly from the forward walls of said peripheral slots, ribbed grinding bars seated in said slots and having lateral projections engaged under 40 said shoulders, forward filler blocks between the bars in the full-length slots and with rearward ends abutting the forward ends of the grinding bars seated in the part-length slots, rearward filler blocks between the bars seated in the part- 45 length slots and those seated in the full-length slots, cover plates closing off the interior of the plug at each end and extending radially beyond the plug surface so as to hold the grinding bars and filler blocks against motion endwise of the 50 plug, said filler blocks being complementarily grooved to engage the ribbed grinding bars by forward motion along the plug.

2. In a machine of the class described, and in combination, a forwardly tapered frusto- 55 conical plug, a pair of peripherally spaced grind-

ing bars attached to said plug, a shorter grinding bar between said bars, locking mechanism between said shorter bar and the plug engageable by forward motion of the bar on the plug, a forward filler between said pair of bars and abutting the forward end of the shorter bar, fillers between the pair of bars and the shorter bar and abutting the rearward end of the said forward filler, and a rearward cover plate extending radially beyond the surface of the plug, 10 all of said bars and adjacent fillers being complementarily ribbed and grooved to hold the fillers on the plug against radial displacement, and the bars and rearward fillers abutting said cover plate. 15

3. In a machine of the class described, and in combination, a forwardly tapered frusto-conical plug, a pair of peripherally spaced grinding bars attached to said plug, a shorter grinding bar between said bars, locking mechanism between 20 said shorter bar and the plug engageable by forward motion of the bar on the plug, a forward filler between said pair of bars and abutting the forward end of the shorter bar, fillers between the pair of bars and the shorter bar and abutting the rearward end of the said forward filler, all of said bars and adjacent fillers being complementarily ribbed and grooved to hold the fillers on the plug against radial displacement. 25

4. In a machine of the class described, and in combination, a forwardly tapered frusto-conical plug, a grinding bar attached to said plug and extending forwardly from its rearward end, a forward filler block adjacent said bar and having tongue-and-groove engagement with it 35 against radial displacement, a second grinding bar extending forwardly from the rearward end of the plug and abutting the rearward end of said filler block, locking mechanism on said second bar and the plug engageable by forward motion of the bar along the plug, and removable means at the large end of the plug and extending radially beyond the surface of the plug so as to hold the second bar against rearward movement along the plug. 40

5. In a machine of the class described, and in combination, the grinding bars 3 having ribs 17, the grooved filler blocks 5, the plug 1 having slots 12 with shoulders 15 spaced along them, the grinding bars 4 seated in slots 12 abutting 50 filler blocks 5 and having projections 16 engaged under shoulders 15, and the rearward cover plate 9 holding said grinding bars 4 against rearward displacement. 45
